(57) **CLAIM**

The ornamental design for an electrode container, as shown and described.

DESCRIPTION

FIG. 1 is a perspective view of an electrode container showing my new design, in the open condition;

FIG. 2 is a front elevation view of the electrode container of FIG. 1, in the closed condition;

FIG. 3 is a rear elevation view of the electrode container of FIG. 1, in the closed condition;

FIG. 4 is a top plan view of the electrode container of FIG. 1, in the closed condition;

FIG. 5 is a bottom plan view of the electrode container of FIG. 1, in the closed condition;

FIG. 6 is a left end elevation view of the electrode container of FIG. 1, in the closed condition; and,

FIG. 7 is a right end elevation view of the electrode container of FIG. 1, in the closed condition.
